UNITED STATES PATENT OFFICE.

JOSEPH C. GITHENS, OF NEW YORK, N. Y., ASSIGNOR TO THE RAND DRILL COMPANY, OF SAME PLACE.

STEAM ROCK-DRILL.

SPECIFICATION forming part of Letters Patent No. 312,348, dated February 17, 1885.

Application filed January 21, 1884. Renewed October 22, 1884. (No model.)

To all whom it may concern:

Be it known that I, JOSEPH C. GITHENS, of New York, N. Y., have invented a Method of and Apparatus for Governing the Rotatory Feed of Steam Rock-Drills and Analogous Engines, of which the following is a specification.

My invention is especially applicable to steam rock-drills of the type in which the rotatory feed is effected by means of a spiral bar free to rotate in one direction only, and playing loosely in a nut in the end of the reciprocating piston which carries the drill, whereby the stroke of the piston in one direction turns the spiral bar to a certain extent upon its longitudinal axis, thus imparting the rotary set to the bar, which in its turn, during the stroke of the piston in the opposite direction, causes the piston to turn upon its longitudinal axis, and to thus turn the drill to a corresponding extent.

The method heretofore employed for preventing the backward rotation of the spiral bar has been by the use of a spring detent pawl or pawls acting upon a ratchet-wheel affixed to the journaled end of the spiral bar.

As the length of the working-stroke in engines of this character is subject to unavoidable variation, owing to variations in the extent of the longitudinal feed, which is governed manually, and the differences in the resistance which the work opposes to the penetration of the tool, it not infrequently happens that the rotatory movement imparted to the spiral bar is of such extent as to carry the radial face or faces of the ratchet tooth or teeth to a point or points slightly in advance of the end or ends of the detent pawl or pawls which bear upon the periphery of the ratchet-wheel. In such cases the first effect of the opposite movement of the piston is to violently turn the spiral bar backward until it is brought up by the collision of the radial face or faces of the ratchet tooth or teeth with the end or ends of the detent pawl or pawls. The shock of this collision or backlash increases the rapidity with which the parts wear and exposes the mechanism to the liability of breakage.

As the strokes of a rock-drill are made

with great rapidity, it has been found necessary to employ strong springs to hold the detent pawl or pawls against the ratchet-wheel. Thus the detent-pawls have acted as brakes upon the ratchet-wheel, materially increasing the amount of power required to effect the rotation of the spiral bar.

Owing to structural peculiarities of the rock-drill engines heretofore employed, the detent-pawls have been applied on one side only of the ratchet-wheel, and the result of their action, therefore, has been to cause an excessive wearing of one side of the journal of the spiral bar.

It is the object of the principal feature of my invention to prevent the possibility of any backward movement of the spiral bar, whatever may be the variations in the length of the strokes of the piston, and the consequent variations in the extent to which the spiral bar is turned while having its rotary set imparted to it. I accomplish this object by the interposition between the face of the wheel affixed to the spiral bar and the wall of a recess formed in the head of the cylinder in which the spiral bar is journaled of a gripping device or devices so arranged as to bind and stop any backward rotation of the spiral bar, while yielding freely to allow the forward rotation of the spiral bar. By the free yielding of the gripping devices in one direction I am enabled to avoid the braking effect incident to the use of the spring detent-pawls heretofore employed, and by the arrangement of several gripping devices, respectively, upon opposite sides of the wheel affixed to the spiral bar the bar is centralized and prevented from wearing its journal unevenly.

My invention is also applicable to steam rock-drills of the class in which the rotatory feed is effected by means of a spirally-formed piston-rod sliding through a rotating nut contained in a stationary chamber, and hence rotating in a fixed plane, in which case the gripping devices are applied between the periphery of the nut and the wall of the chamber in which the nut is contained.

The accompanying drawings, representing so much of a rock-drill engine as is necessary to exhibit my improvement, are as follows: 10c

Figure 1 is a central longitudinal section of a portion of the cylinder, showing the spiral bar and a portion of the piston in side elevation. Fig. 2 is an end view, partly in section, through the line X X on Fig. 1, showing the wheel affixed to the journaled end of the spiral bar, and several friction-rollers interposed between the teeth of the wheel and the wall of a recess formed in the head of the cylinder.

Fig. 3 is a top view of the cylinder.

The drawings show the cylinder A of a rock-drill engine and one of the steam-passages B, leading from the valve-chest. The piston C has the usual piston-rod, C', affixed to it at one end, and is longitudinally recessed at the opposite end to admit the spiral bar D, which fits loosely, so that it can slide in the nut D' fastened in the outer end of the recess D² in the piston. The spiral bar is provided with a journal, a, in the cylinder-head A', which is countersunk to form the cylindrical recess a', for containing the wheel or hub d, affixed to the outer end of the spiral bar D. The periphery of the wheel or hub d is notched, and the bottoms of the notches present the eccentric faces d'. A cylindrical friction-roller or rolling stop, E, is deposited in each of the notches formed in the wheel or hub d. The arrow F in Fig. 2 indicates the direction in which the spiral bar is free to rotate. An expanding spiral spring, e, is seated in the radial side of each notch and presses the roller in front of it toward the narrower part of the space between the bottom of the notch and the wall of the recess a'. On one side the roller bears upon the concentric wall of the recess a', and on the other side upon the eccentric face d', forming the bottom of the notch in which it is deposited. The diameter of the roller is slightly less than the width of the space between the recess a' and the deepest part of the notch in which it is deposited. By the action of the expanding spring the roller is pressed forward, so that it bears upon the bottom of the notch in which it is deposited and the wall of the recess a'. Each roller, therefore, occupies a position which prevents any backward rotation of the spiral bar, while not interfering with the forward rotation of the bar in the direction indicated by the arrow, because by such rotation the roller is carried back into the wider part of the space between the bottom of the notch and the wall of the recess a'.

In the drawings the wheel or hub d of the spiral bar is represented as having four notches, between the bottoms of which and the wall of the recess a' are interposed four friction-rollers, E, respectively. It will of course be understood that the number of notches in the hub and the number of friction-rollers employed may be either increased or diminished, if desired, without departing from so much of the invention as resides in the employment, in combination with a piston and spiral bar, of a frictional gripping device which binds

between the hub of the spiral bar and the cylinder-head in such a way as to prevent any backward rotation of the spiral bar; and, further, it will be seen that the friction-rollers E do not oppose any appreciable resistance to the rotation of the spiral bar in the desired direction, and that by arranging several friction-rollers upon opposite sides of the center of the spiral bar they serve to centralize the bar in its journal. The cylinder-head A' is provided with a cap, A², which is secured in position by means of the usual longitudinal bolts, G G, extending through both heads of the cylinder, and provided with the nuts g g. A shorter bolt, H, provided with a nut, h, cooperates in securing the cap A² upon the head A', and is made hollow and provided with an internal screw-thread for engagement by the thread of the usual adjusting-bolt, by means of which the longitudinal feed is given to the cylinder.

No special description of the valve-gear is required, because it is immaterial for the purposes of the present invention what kind of valve-gear is employed.

By the described method of effecting and controlling the rotatory feed of the piston it will be seen that the extent of the rotatory feed of the piston, and consequently of the tool carried by the piston, is in all cases exactly equal to the extent to which the spiral bar is turned during that movement of the piston by means of which the rotatory set is imparted to the spiral bar. It thus follows that in case of a short stroke of the piston there will be a less extent of rotatory feed of the drill than there is when the piston makes a long stroke. This is important, because when the piston makes a short stroke the force of the next succeeding blow is diminished, and it is therefore desirable that there should be a smaller extent of rotatory feed than in those cases where the piston makes a longer stroke. By my invention, therefore, the rotatory feed of the drill is varied according to the variations in the length of the stroke of the piston. This result is accomplished by making the extent of the rotatory feed dependent in all cases upon the length of the working-stroke of the piston—that is, the length of the stroke by which the tool is driven against the rock—because it is during the working-stroke of the piston that the rotatory set is imparted to the spiral bar, the rotatory feed of the piston and tool being effected during the return-stroke of the piston, at which time the spiral bar is held stationary.

In applying my invention to the class of steam rock-drills in which the piston-rod is given a spiral form and slides through a nut loosely contained in a stationary chamber, the friction-rollers are deposited in suitably-shaped recesses between the nut and the wall of the chamber containing the nut. In this application of my invention the spirally-formed piston-rod is the equivalent of the

spiral bar, and the nut contained in the stationary chamber is the equivalent of the nut affixed to the piston; and the friction-rollers acting on a nut revolving in a fixed plane, and 5 engaging an endwise-reciprocating spiral piston-rod or spiral bar affixed to the piston, are the equivalents of the friction-rollers acting on the head of a spiral bar rotating in a fixed plane and engaging a nut affixed to, and hence 10 reciprocating with, the piston.

I claim as my invention—

1. In a rock-drill or other analogous engine in which the piston is liable, when the machine is in operation, to make strokes of variable length, and in which the rotatory feed of the piston is effected by means of a spiral bar loosely engaging a nut formed in or affixed to a longitudinally-recessed piston, the combination of the said spiral bar and piston with 15 the herein-described mechanism for definitely varying the extent of the rotatory feed following different working-strokes of the piston proportionately to differences in the lengths of such different working-strokes, the said 20 mechanism consisting of a rolling stop or stops deposited in a recess or recesses between the interior surface of a chamber formed in the head of the cylinder, and a portion of the head of the spiral bar, or of a wheel or collar 25 affixed to the end of the spiral bar, and constituting the head thereof, and a spring or springs acting to force such rolling stop or stops, respectively, toward the narrower part 30 or parts of the recess or recesses containing 35 the said rolling stop or stops.

2. In a rock-drill or analogous engine, a longitudinally-recessed piston and a spiral bar journaled in the cylinder-head and loosely engaging a nut affixed to the piston, and provided near its journal with a wheel or hub 40 having in its periphery a series of notches, the bottoms of which present eccentric faces, in combination with a cylindrical recess formed in the head of the cylinder, and a series of friction-rollers deposited, respectively, in the 45 notches of the said wheel or hub, and a corresponding series of springs supported in said wheel or hub, and exerting their tension in such a direction as to force the rollers, respectively, toward the narrower parts of the 50 spaces between the concentric wall of the recess and the eccentric faces which constitute the bottoms of the notches.

3. In combination with the herein-described spiral bar and piston, two or more rolling 55 stops arranged upon opposite sides of the head of the spiral bar, and interposed between the head of the spiral bar and the interior surface of a chamber formed within the head of the cylinder, for the purpose of centralizing the spiral bar and preventing it from 60 wearing its journal unevenly, substantially as described.
